DESIGN FOR A CHILD'S VEHICLE

Harry P. Joyce, Beverly Hills, and Mathias Kreppel, Los Angeles, Calif., assignors to James L. Kenyon, Los Angeles, Calif.

Application July 11, 1946, Serial No. 131,506

Term of patent 3½ years

(Cl. D34—15)

To all whom it may concern:

Be it known that we, Harry P. Joyce and Mathias Kreppel, citizens of the United States, residing at Beverly Hills and Los Angeles, respectively, in the county of Los Angeles and State of California, have invented a new, original, and ornamental Design for Child's Vehicle, of which the following is a specification, reference being had to the accompanying drawing forming a part thereof:

We claim:

The ornamental design for a child's vehicle, as shown.

HARRY P. JOYCE.
MATHIAS KREPPEL.
